(57) **CLAIM**

The ornamental design for a key bow, as shown and described.

DESCRIPTION

FIG. 1 is an isometric view of the key bow of the invention; FIG. 2 is a first side elevation of the key bow of FIG. 1; FIG. 3 is an end view of the key bow of FIG. 1; FIG. 4 is an opposite side view of the key bow of FIG. 1; and,

FIG. 5 is a rear end view of the key bow of FIG. 1. The broken-line disclosure on the bow, and broken-line disclosure of the shank element in the views are for illustrative purposes only and form no part of the claimed design.
